DESIGN FOR A PLUG VALVE BODY UNIT

Eugene C. Brisbane, York, Pa., assignor to S. Morgan Smith Company, York, Pa., a corporation of Pennsylvania

Application November 5, 1937, Serial No. 72,636

Term of patent 14 years

To all whom it may concern:

Be it known that I, Eugene C. Brisbane, a citizen of the United States of America, residing at York, in the county of York and State of Pennsylvania, have invented a new, original, and ornamental Design for a Plug Valve Body Unit, of which the following is a specification, reference being had to the accompanying drawings, forming part thereof, in which

Figure 1 is a perspective view of a plug valve body unit, showing my new design;

Fig. 2 is a plan;

Fig. 3 is a front elevation; and

Fig. 4 is a side elevational view thereof.

I claim:

The ornamental design for a plug valve body unit, as shown.

EUGENE C. BRISBANE.
